MEANS FOR FACILITATING ESCAPE FROM
SUBMERGED CRAFT

Angelo Belloni, La Spezia, Italy

Application April 9, 1936, Serial No. 73,569
In Italy May 3, 1935

6 Claims. (Cl. 114—16.6)

The present invention has for its object an arrangement which permits individuals, who may be members of the crew, to leave and re-enter submersibles when these craft are submerged at any depth not greater than 100-120 metres. The arrangement is such that it is applicable either to newly built submersible vessels, or to existing ships, that are fitted with the requisite known form of hatchway, or are capable of being fitted with the same.

It is known to provide submersible craft with a barometric lock for each of the two fore and aft ordinary hatchways, by using a rigid or collapsible tube, secured with a water-tight joint beneath the lower scuttle of the hatchway and extending downwardly therefrom, in combination with a fixed or collapsible tank installed on the floor of the compartment beneath the hatchway, the upper edge of which tank is at a level above that of the lower edge of the downwardly extending tube.

According to the present invention however, escape from submerged craft through hatchways in the fore and aft compartments is facilitated by means comprising a collapsible canvas tank installed on the floor of the refuge compartment and secured at one of its sides by a water-tight joint to the frame of a watertight door in the side of the hatchway, in such a manner that the door itself may be shut or opened inside the tank, which is flooded together with the "lock", or the lower portion of the hatchway.

The means according to the present invention are illustrated by way of example in the accompanying drawings in which:

Fig. 1 is a diagrammatic vertical section through a compartment fitted with the means according to the present invention, the various doors being shown in positions which they might occupy when the submersible is floating on the surface of the water.

Fig. 2 is a diagrammatic horizontal cross section of the compartment shown in Fig. 1.

Fig. 3 is an outside end view of the compartment illustrating a detail to be described later.

Figs. 4, 5 and 6 are diagrammatic vertical sections of the compartment and show how the crew of a submerged vessel can escape by performing an "air-lock" manoeuvre.

Referring to the drawings, a collapsible tank 1 on the floor of the refuge compartment is secured by a watertight joint to the vertical frame of the watertight door 2 which opens towards the tank from the lower part 3 of the hatchway 3, 4. The hatchway has an outer door 7'

and an inner door 7, which divides the upper part 4 from the lower part 3 of the hatchway. The door 7' shown in the drawings and lying above the collapsible tank 1 plays no part in the operations of escaping from the vessel when submerged and forms no part of the present invention. It may be opened when the vessel is on the surface to permit torpedoes to be taken on board. The hatchway 3, 4 has the form of a fixed, rigid tube and the upper edge 5 of the 10 collapsible tank is at a level above that of the upper edge 6 of the watertight door 2, which is in effect the lower edge of the barometric tube in the resulting barometric lock.

With this arrangement, since the watertight 15 door 2 will always be capable of being opened or shut inside the tank 1, it will be possible to provide for escaping either by a "barometric" manoeuvre or by an "air-lock" (or equilibrium) manoeuvre, the former being absolutely necessary when the refuge compartment attains a high pressure, and the latter being advisable whenever the depth is more than 30-40 metres.

Suppose now that the vessel is submerged, that the doors 7, 7' and a valve 13 connecting the tank 1 with the lower part 3 of the hatchway are closed and that members of the crew are to escape by an "air lock" manoeuvre. First of all a member of the crew climbs the ladder 12, enters the tank 1, passes through the door 2, opens the door 7 and unlocks, but does not open and he cannot open the door 7'. He then returns to the refuge compartment closing the door 2 after him. The next step is to open a sea cock 30 13' and thereby flood the hatchway 3, 4. The air displaced by the water which enters the hatchway escapes through an air-vent 13" in the top of the chamber 4 into the refuge compartment. Meanwhile the valve 13 has been 35 opened and water continues to enter the tank 1 until the water in the tank 1 reaches the level 8 (Figs. 4, 5, 6). The valve 13 is then closed. As soon as water instead of air is ejected from the air-vent 13" in the top of the upper part 40 4 of the hatchway, the said air-vent is closed also. When the water pressure inside the hatchway equals the water pressure outside the vessel, the sea cock 13' is turned off and the door 7' is opened by means of a special handle 14' accessible from the refuge compartment. The door 7 is then lowered by means of the handle 14; and the valve 13 is opened. The water inside 45 both the tank 1 and the lower part 3 of the hatchway thus gradually assumes the level 8, 50 55

- whilst surplus water escapes from the tank 1 through an overflow pipe 8' which prevents the water level in the tank rising above the level 8. The valve 13 is then shut and the door 2 opened.
- 5 A first party of two, three or four men fitted with submarine autorespirators and watertight dresses now climb up the ladder 12, enter the tank 1 and pass through the door 2 into the lower part 3 of the hatchway (see Fig. 4). An-
10 other member of the crew wearing the water-
tight dress then shuts the door 2 from inside the tank 1; after which he may leave the tank 1 so as to avoid getting cold. As soon as the door 2 is shut, one of the men inside the lower
15 part 3 of the hatchway opens a conduit 15 through which compressed air is supplied in order to raise the pressure in the lower part 3 to that of the surrounding water (see Fig. 5). As soon as the pressures in the parts 3 and 4
20 of the hatchway are balanced, the door 7 is opened, air escapes from 3 through 4 and water takes its place and fills up the lower part 3 of the hatchway. This takes place more rapidly if one of the crew, standing inside or outside the
25 tank 1, forces open the door 7 by means of the handle 14. The sooner this is done the better, since the time taken by members of the crew to become accustomed to reduced pressure depends on the time they have been subjected to high
30 pressure. When the door 7 is open the member of the crew who is least affected by changes in pressure leaves the vessel first, floating up through the reserve-buoyancy of his respirator. He takes hold of a cable, such as that of the telephone
35 buoy, on which stopping points are marked with knots and the other members of the crew follow him (see Fig. 6). As soon as the members of the crew in the refuge compartment see through a spy glass 16' that the part 3 is empty (for this
40 purpose a lighted diving lamp is arranged inside the lower part 3 of the hatchway), they shut the door 7 with the aid of the handle 14. Further parties of the crew can now escape in the same way as the first party already referred to. Al-
45 though an "air-lock" manoeuvre, such as that described above, is the safest when escaping from a depth of more than ten to fifteen fathoms, it is sometimes preferable to make use of a "barometric" manoeuvre, which is more rapid although less
50 safe. For example the "air-lock" manoeuvre might be too slow if the air pressure in the refuge compartment were to increase rapidly due to leak-
ages in the water-tight bulk-head, or if chloride
gases were present.
- 55 When performing a "barometric" manoeuvre first of all the parts 3 and 4 of the hatchway are flooded with the door 2 shut, doors 7, 7' open. The tank 1 is then flooded by means of the valve 13 until the water reaches the level 8 (Fig. 6). The air pressure in the refuge compartment is then raised by admitting compressed air through a vent 15' in known manner. In order to save compressed air and to equal the pressure of the surrounding water as soon as possible, the refuge
60 compartment may be flooded until about half full of water. If this is done it may not be necessary to admit compressed air through the air vent (i. e. at nearly 5 fathoms depth).
- 65 As soon as the crew observe, from a suitable instrument (such as a high pressure barometer together with a depth manometer 17''), that the pressures are balanced, one of them opens the door 2 and they all leave the vessel, one after the other, by way of the ladder 12, the tank 1, the door 2, the part 3 of the hatchway, the door 7,

the part 4 of the hatchway, the door 7' and take hold of the cable outside.

In both cases, the arrangement described prevents escape of air and the consequent inrush of water through the hatchway, which otherwise might easily occur in rough sea, since the combined action of the inner scuttle 7 of the hatchway and of the door 2 ensures a constant pressure in the refuge compartment, and a constant water level in the tank.

10 Figs. 4, 5 and 6 show how the "air-lock" manoeuvre is performed with the aid of this installation and also show clearly how the principal advantage of this special system of escaping can be obtained, namely, the shortest possible time for attaining the necessary pressure inside the "lock" 3 (or lower room 3 of the tubular hatchway 3, 4) and consequently the smallest danger of embolism for men, when emerging from great depths. Instead of 40-50 minutes being required for attaining a pressure of 10 atm. as would be the case with a barometric manoeuvre, we can obtain this same pressure in 4-5 minutes, as shown by the most recent experiences on board Italian submarines, using a very small amount of compressed air.

15 A further feature of the present invention is shown by Figure 3. In submarine vessels fitted with known forms of hatchway it was practically impossible to use the tank, either for barometric or for "air-lock" (or "equilibrium") escape, if the 20 boat was not lying on an even keel, but steeply on her bow or on her beam-ends. Since a steep inclination would be sufficient not only to cause water to pour into the compartment by over-flowing the upper edge 5 of the tank, but also to 25 cause the water-level 8 in the tank itself on one side to descend below the upper edge 6 of the door 2 (Fig. 3) or, in other words, the lower edge of the tube 4, escape of air from the compartment was possible. Such an escape of air would of 30 course result in the air pressure in the compartment itself being reduced and in the inrush of considerable quantities of water through the hatchway. According to the present invention, 35 the upper edges of the inner rubber-cloth tank, are "bonneted" as high as the ceiling of the compartment, by the cloth addition 9, which is adapted to be raised from the lower side of the tank and fastened to the ceiling. In this way, a 40 new water-level 10 can be reached without any 45 danger of escape of air and inrush of water.

50 Obviously, when the "bonnet" 9 is raised, men can get into the tank from the upper side 11 of the tank, where the "bonnet" is left loose.

55 What I claim is:

1. Apparatus for facilitating escape from a submerged vessel, comprising a hatchway in the vessel having upper and lower chambers, a door between the hatchway chambers, a refuge compartment in the vessel, a collapsible tank in the refuge compartment, a water-tight door in the side of the lower hatchway chamber, said door providing communication between said chamber and the tank and being operable from inside the tank, and means for flooding said tank and lower hatchway chamber.

60 2. Apparatus for facilitating escape from a submerged vessel, comprising a hatchway in the vessel having upper and lower chambers, a door between the hatchway chambers, a refuge compartment in the vessel, a collapsible tank in the refuge compartment, a water-tight door in the side of the lower hatchway chamber, said door providing communication between said chamber and the tank and being operable from inside the

5 tank, means for flooding said tank and lower hatchway chamber, and means for establishing a predetermined water level in the tank and lower chamber when the door between the hatchway chambers is lowered and the door between the lower hatchway chamber and the tank is closed.

10 3. Apparatus for facilitating escape from a submerged vessel, comprising a hatchway in the vessel having upper and lower chambers, a door between the hatchway chambers, a refuge compartment in the vessel, a collapsible tank in the refuge compartment, a water-tight door in the side of the lower hatchway chamber, said door 15 providing communication between said chamber and the tank and being operable from inside the tank, means for flooding said tank and lower hatchway chamber, and means for admitting compressed air into the lower hatchway chamber when the door between the hatchway chambers is lowered and the door between the lower chamber and the tank is closed.

20 4. Apparatus for facilitating escape from a submerged vessel, comprising a hatchway in the vessel having upper and lower chambers, a door between the hatchway chambers, a refuge compartment in the vessel, a collapsible tank in the refuge compartment, a water-tight door in the side of the lower hatchway chamber, said door 25 providing communication between said chamber and the tank and being operable from inside the tank, means for flooding said tank and lower hatchway chamber, and a door in the outer wall of the upper hatchway chamber.

5 5. Apparatus for facilitating escape from a submerged vessel, comprising a hatchway in the vessel having upper and lower chambers, a door between the hatchway chamber, a refuge compartment in the vessel, a collapsible tank in the refuge compartment, a water-tight door in the side of the lower hatchway chamber, said door 10 providing communication between said chamber and the tank and being operable from inside the tank, means for flooding said tank and lower hatchway chamber, means for admitting compressed air into the lower hatchway chamber when the door between the hatchway chambers is lowered and the door between the lower chamber and the tank is closed, and means for operating the door between the hatchway chambers from inside the refuge compartment.

15 6. Apparatus for facilitating escape from a submerged vessel, comprising a hatchway in the vessel having upper and lower chambers, a door between the hatchway chambers, a refuge compartment in the vessel, a collapsible tank in the refuge compartment, a water-tight door in the side of the lower hatchway chamber, said door 20 providing communication between said chamber and the tank and being operable from inside the tank, means for flooding said tank and lower hatchway chamber, and a bonnet on the top of the collapsible tank, said bonnet being capable of upward extension sufficiently to allow a higher 25 free water level in the tank without flooding the refuge compartment when the vessel is not on even keel or is lying on its beam-ends.

ANGELO BELLONI.
